UNITED STATES PATENT OFFICE

STANTON W. FORSMAN, OF PASADENA, CALIFORNIA

SHIPPING CONTAINER AND BLANK FOR MANUFACTURING THE SAME

Application filed September 9, 1930. Serial No. 480,639.

This invention relates to the art pertaining to that type of one-piece shipping containers and board for making the same having an indurated facing strengthened by a cellular structure as set forth in Letters-Patent of the United States, No. 1,161,818, granted to me November 25, 1915; and an object is to provide improved blanks and containers of said type.

10 So-called one-piece solid fiber board containers in current use are secured in set-up or cubic form by wire stitching or stapling.

Heretofore, the use of wire stitched boxes made of faced cellular board has been found 15 impractical for the reason that the wire stitching or stapling breaks through such faced cellular board so that the joint or seam is insecure.

20 The use of gummed tape for closing the joints is not found perfectly satisfactory for the reason that said tape is not desirably strong, and under wet conditions it is subject to become loosened and pulled away from the board.

25 An object is to provide a stronger construction of faced corrugated container and to avoid the dependence upon an adhesive for holding the closed container together; and to make the seam of the faced corrugated container practically proof against pulling apart under wet conditions.

30 An object of this invention is to provide a double faced corrugated board container of such construction that all of its parts can be fastened by wire stitching.

35 Another object is to make a more perfect closure against the ingress of insects, dust and dirt; thus to make the container more acceptable for storage and shipment of loose raisins and other products subject to injury from contact of, or mixture with, dust or other foreign material.

40 A feature of the invention resides in the construction of the board and the forming of the body out of five hinged panels, and the securing of the first and fifth panels together by mechanical fastening means such as by wire stapling or stitching.

45 The invention is applicable in various forms and in some cases may be embodied

with corrugated board constructed with single ply facings. Preferably indurated multiple ply facings are employed.

The more particular advantages aimed at, are the strength of construction and the exclusion of insects, dust and dirt.

55 It is understood that it is customary in providing blanks for large containers, to stitch together two or more sections of faced cellular or corrugated board to form one large blank, and I use the term one piece blank and one piece container as inclusive of blanks cut in one piece at the outset, or blanks originally cut in two or more pieces that are stitched or taped together to form the blank ready for folding into cubical form.

60 The term length herein is simply used to denote the dimensions along or parallel to the creases and is not indicative of comparative dimensions.

70 The terms top and bottom where used in the specification refer simply to the top and bottom of the views in the drawing and not to the completed container.

75 The term closure will be used to designate thick stiff leaves serving to partly or fully close the ends of the completed container.

80 A feature of the invention is the provision of closures having relatively thin flaps formed by an outer skin and adapted to be fastened to an adjacent closure.

85 Other objects, advantages and features of invention may appear from the accompanying drawing, the subjoined detailed description and the appended claims.

85 The accompanying drawing illustrates the invention in two forms of construction.

90 Figure 1 is a view of the inner side of a slotted and paneled blank of double faced board of one piece comprising a corrugated filler, a two-ply indurated inner face and a three-ply indurated outer facing or skin; portions of the blank being broken away and portions shown displaced to expose construction of the blank that would not otherwise appear in this view.

95 Fig. 2 is an unbroken elevation of the blank viewed from the left of Fig. 1; the thickness of plies of the facings being exaggerated.

100 Fig. 3 is a view analogous to Fig. 2, show-

ing the blank from the right end of Fig. 1.

Fig. 4 is an edge elevation of the blank looking up from below Fig. 1.

Fig. 5 is a view of a container made from the form of blank shown in Figs. 1-4, the upper end of the container being open, ready for closing, and a portion of its left end being broken to expose the stitching and interior construction.

10 Fig. 6 is a view of the container sealed by stitches.

Fig. 7 is an enlarged fragmental longitudinal section on line x_7-x_7 , Fig. 6, of a container constructed in accordance with this 15 invention so far as the same is applicable to a container formed of a blank having only single ply internal and external facings.

Fig. 8 is an enlarged fragmental transverse section on line x_8-x_8 , Fig. 6 of a container 20 analogous to that shown in Fig. 7.

The container in Figs. 1-6 is composed of a creased and slotted bent-up one-piece blank with outer skin extensions and suitable stitching or stapling.

25 The creased and slotted blank comprises a line of four body panels 1, 2, 3, 4, and a terminal stitching panel or lap 5, of equal length. Said blank is composed of three sheets cemented together face to face and 30 forming an outer facing skin 6, inner facing or liner 7 and a corrugated filler 8 between the facings; and the double faced cellular board is thus made of such stiffness and strength as may be required.

35 The blank has four transverse and two longitudinal creases on its inner side, there being three transverse creases 9 to afford flexible lines permitting the blank to be bent with the skin 6 outside; the corrugated filler 40 being crushed along the creases so that the blank material at the creases forms hinges between adjoining panels 1, 2, 3, 4; and a corresponding crease 10 between the fourth panel 4 and the stitching lap 5, serves in 45 the same manner to hinge panel 4 and the lap 5 together.

At opposite ends of the panels 1, 2, 3, 4, there are provided two lines of bottom closures 11, 12, 13 and 14 and top closures 50 11', 12', 13' and 14'; and the blank material at the longitudinal creases 15 like that at the transverse creases 9 and 10, fits the sheet material for hingedly connecting the panels and the closures together.

55 The blank is provided with slots 16, 17, 18, extending from the longitudinal creases 15 to the edges of the outer indurated facing 6 which extends outward beyond the outer edges of the closures to form flaps 19, 20, and 60 21, for the first, second and third closures 11, 12, and 13, and 11', 12' and 13' that are at the ends of the first three panels.

The skin 6 does not extend beyond the edges of the closures 14, 14', which may be termed 65 stub closures, while the closures 11, 12, 13,

and 11', 12', 13' may be termed the flap closures.

In the form of double faced corrugated board shown in Figs. 1-6, the outer facing or skin 6 is made of three plies *a*, *b*, *c*, and the inner facing 7 is formed of two plies *d* and *e*, and in practical use, when the container is formed in a manner that is obvious from the drawing, and analogous to that known to the box makers art, bringing the closures 11 and 75 13 toward each other into closing position, the sealing flaps 19, 20, 21, of the skin are overlapped and are then secured by the stitching 22 which is effected by the operation of the usual stitching machine, well known in the art of stitching solid fiber board containers.

80 In the form shown in Figs. 7 and 8, the double faced corrugated board is made with single sheet outer and inner facings as shown at 6' and 7' and it is understood that where it may be desired, the outer skin sealing flaps 19, 20, 21, may be cemented on the outer sides of the closures 11, 12, 13; but that for greater strength of package, the thicker multiple ply 85 external facing or skin is preferred for the purpose of affording greater strength for packing fragile ware or goods or materials that are likely to be crushed when packages having heavy contents are piled in tall 90 columns.

95 In practical manufacture the inner indurated sheet 7 and corrugated sheet 8 for the blanks are stamped or cut out by a suitable die, not shown, in a manner which will be well understood by those skilled in the art; and the outer indurated sheet or skin 6 may be readily stamped or cut out by a die, not shown, which die conforms to the outer skin sheet 6, including the six flaps 11, 11', 12, 12', 13, 13', as shown in Fig. 1. Then the three sheets will be cemented together to form the blank shown in Fig. 1, and the blanks are then ready for use and may be baled and shipped in quantities to the place where they are to be assembled and used.

100 In common practise it is deemed preferable to stitch the stitching panel to the panel 1 at the factory and then ship the product as knocked down containers to the place of use, where they will be set up as hereinbefore explained, and their flaps or closures cemented or stitched together.

105 The method of assembly will be readily understood by those skilled in the art, it being simply necessary to first bend the blank at the hinge creases 9, 10, to form a hollow prism, with the stitching panel or lap inside as indicated in Fig. 5; and then the stitching lap panel 5 will be stitched to the end panel 1 in any suitable manner as indicated at 115 22 in Fig. 5, and the flaps will be sealed by stitching, or with any suitable cement, and the package is completed.

110 In practise, the creased and slotted board is set up into cubical form by first bringing 120

the body panels 1, 2, 3, 4, the stitching panel 5, and the closure panels into the form of a prism, rectangular in cross-section, and open at both ends, then fixing the stitching 5 panel 5 and the first body panel 1 together by the stitches 22. Then the closures 11 and 13, and their flaps at one end of the prism will be folded toward each other and with the closures arranged to extend transversely at 10 right angles to the panels. The closures 14 will be folded over in like manner, and the closure 12, and its flap 20 and the closure 14 will be folded into the prism form at right angles thereto and closure 14' will be folded 15 to bring the edges of the closures 12' and 14' adjacent to, or in abutment against each other.

The bottom flaps 20 formed of the outer indurated facing or skin 6 are brought across 20 the closure 14 and stitched or cemented thereto, and the open container set up shown in Fig. 5, is then completed, ready to be charged with the approved commodity; and thereupon the top closures will be folded in the 25 manner above described and the flap 20' will be stitched or cemented to the closure 14'.

The stitching may be readily effected by a well known wire stapling machine, not shown, having a flat, thin clinching anvil 30 arm, not shown, adapted to be inserted between the folded stub closure 14 or 14' and the flap closures as 11 and 13, or 11' and 13', thus completing the filled package.

In the form illustrated in Fig. 7, the stitching panel or lap 5 is omitted and the panel 4" is made wider than the panel 2" so as 35 to extend over the edge of, and terminate flush with the outer face of panel 1", and the joint is there secured and sealed with a 40 strip of gummed tape, 22'.

The panels 1, 2, 3, 4, go to make up the four walls of the completed hollow prism, and the closures 11, 11', 12, 12', 13, 13', 14 and 14' form end extensions of the panels preparatory to folding over of the closures to close 45 the ends of such prism, and the outer skin facing is effective in forming flaps extending from closure edges for the purpose of sealing the completed prism ends by securing 50 ment of opposite closures to each other through flap means.

Preferably, for the greatest security against breakage of seams and exclusion of ingress at the joints, the surfaces of the 55 blanks which contact with each other are sealed with sodium silicate cement; and since it is customary to use such substance in the cementing together of the corrugated filler and the skin surfaces, the closed package is 60 practically proof against moisture, insects, dust and dirt, as well as being stronger for a given thickness of board and weight and size of package.

It is found that rodents do not gnaw 65 through the container walls made up of the

sheets cemented together with sodium silicate and that the combination of strength, imperviousness, and permanency are notably included in the completed construction herein set forth.

70

I claim:—

1. A blank for constructing containers which comprises a corrugated or cellular filler and outer and inner facing sheets cemented on such filler; said blank having four transverse and two longitudinal creases on its inner side; the filler being crushed at such creases and the blank comprising four body panels and a terminal stitching panel hinged together by the blank material at the creases, 75 the ends of said panels being bordered by the longitudinal creases; closures hinged to the body panels respectively by the blank material at the longitudinal creases; the length of the edge of each closure hinged to its panel 80 being nearly as great as the length of the edge to which such closure edge is hinged; and sealing flaps formed of the outer facing and extending outwardly beyond the edges of the three closures which are the farthest 85 removed from the stitching panel; said blank being provided with slots alined with the transverse creases and extending from the body panels to the outer edges of the flaps.

2. A double faced corrugated board con-

95

tainer which comprises a corrugated filling, a multiple ply outer facing sheet, and an inner facing sheet, cemented on such filling; said board having four transverse and two longitudinal creases on the inner side of the board; the filler being crushed at such creases and the board comprising four body panels, a terminal stitching panel and six closures; the ends of said panels being alined and bordered by the longitudinal creases; the clo- 100 sures being hinged to the body panels by the board material at the longitudinal creases; and sealing flaps formed of the outer facing and extending beyond the edges of the adjoining closures; said board being provided 110 with slots alined with the transverse creases and extending from the body panels to the outer edges of the board and the sealing flaps; the panels and closures being set up to cubic form and each outer flap extending from its 115 closure over the joint between such closure and the adjacent closure and fixed to such adjacent closure.

3. A double faced corrugated board con-

120

tainer which comprises a corrugated filling, a multiple ply outer facing sheet, and an inner facing sheet, cemented on such filling; said board having four transverse and two longitudinal creases on the inner side of the board; the filler being crushed at such creases 125 and the board comprising four body panels, a terminal stitching panel and six closures; the ends of said panels being alined and bordered by the longitudinal creases; the clo- 130 sures being hinged to the body panels by the

board material at the longitudinal creases; and sealing flaps formed of the outer facing and extending beyond the edges of the adjoining closures; said board being provided
5 with slots alined with the transverse creases and extending from the body panels to the outer edges of the board and the sealing flaps; the panels and closures being set up to cubic form and each flap extending from
10 its closure over the joint between it and the adjacent closure and stitched to such adjacent closure.

4. A double faced corrugated board container which comprises a corrugated filling, an outer facing sheet, and an inner facing sheet, cemented on such filling; said board having four transverse and two longitudinal creases on the inner side of the board; the filler being crushed at such creases and the
20 board comprising four body panels, a terminal stitching panel and six closures; the ends of said panels being alined and bordered by the longitudinal creases; the closures being hinged to the body panels by the board material at the longitudinal creases; and sealing flaps formed of the outer facing and extending beyond the edges of the adjoining closures; said board being provided with slots alined with the transverse creases and extending from the body panels to the outer edges of the board and the sealing flaps; the panels and closures being set up to cubic form and each flap extending from its closure over the joint between it and the adjacent closure and stitched to such adjacent closure.

5. A blank of the character set forth comprising four panels hinged together; closures hinged to the ends of the panels respectively, and adapted to be folded therewith to form a hollow prism; the blank having a skin facing forming flaps extending from closure edges for the purpose of sealing the prism ends by securement of opposite closures to each other through flap means; sodium silicate cement securing flaps and folders together; and stitching extending through flaps and folders and securing the same together.

In testimony whereof, I have hereunto set my hand at Los Angeles, California, this 2nd day of September, 1930.

STANTON W. FORSMAN.
